UNITED STATES PATENT OFFICE.

DAVID W. BROWN, OF NEW YORK, N. Y.

PROCESS OF UTILIZING HIGH-FREQUENCY ELECTRICAL OSCILLATIONS.

1,319,990.

Specification of Letters Patent. Patented Oct. 28, 1919.

Application filed August 27, 1917. Serial No. 188,524.

To all whom it may concern:

Be it known that I, DAVID W. BROWN, a citizen of the United States, residing in the borough of Manhattan, city, county, and State of New York, have invented certain new and useful Improvements in the Processes of Utilizing High-Frequency Electrical Oscillations, of which the following is a specification.

This invention relates to improvements in processes of utilizing high frequency electric oscillations, and especially for increasing the effect of such oscillations upon detectors.

In my application for United States Letters Patent filed May 26, 1917, Serial Number 171,092, I have set forth apparatus for said purpose, and the present invention is especially adapted to be operated with said apparatus, but is not limited to use therewith.

When Hertzian waves, sent out from a sending station, are received on the antennæ and aerials of receiving stations, such waves set up high frequency electric oscillations on said antennæ and aerials, which affect detectors, and are thereby ultimately enabled to produce various desired results at the receiving stations, such as the production of signals, explosions of explosive substances, control of machinery and other desired results. But, as the said Hertzian waves radiate from the antennæ of the sending station through space to the antennæ of the receiving station, their strength diminishes, and the high frequency oscillations set up by them at the receiving station also become correspondingly weaker and unable to properly affect the detectors and produce the desired results.

It is therefore the purpose of the present invention to provide a process for increasing the effect of high frequency electric oscillations upon detectors, so that even such oscillations which without this invention, would be too feeble to properly affect the detectors, will, by the use of this invention, be, as it were, so reinvigorated or strengthened, and have their effect upon the detectors so increased, that they will properly affect the detector and enable the desired results to be ultimately produced.

The invention proceeds upon the following principles: Whenever an electric current flows along a wire, there is developed a field of electro-magnetic force all around said wire. The electricity of the ordinary continuous or constant electric current does not substantially differ in its kind or nature from an alternating current of electricity, or from an electric current which oscillates very rapidly, and which is termed in wireless telegraphy, "a high frequency oscillating current." But said constant current, said low frequency alternating current, and said high frequency oscillating currents are all of the same substantial nature, and, therefore, when electricity of one kind is directed into the field of electricity of another kind, the several kinds of electricity become added together algebraically. By "algebraically", I mean, for example, that supposing that the independent constant current is positive in its direction, then the field thereby developed around the aerial will increase the strength of those vibrations of the high frequency oscillations which are in the positive direction, and will decrease the strength of those high frequency oscillations which are in the negative direction, and the effect of said oscillations, in the total, upon detecting instruments will be increased. Therefore, if high frequency oscillations are caused to pass through a field which is produced by constant currents, there will in every case be produced a certain algebraic increase in the strength of said high frequency oscillations, and in the effect said high frequency oscillations will produce upon the detecting instruments. Now, in this present invention I cause a continuous flow of constant current electricity to proceed along a certain part of the aerial wire, which provides the path for the high frequency oscillations, when said high frequency oscillations are produced on the antenna by Hertzian waves which come from the distant sending station. This constant current, being continuous, is always flowing on the aerial, and therefore there is always produced and is always existing a constant field of electro-magnetic energy around the aerial, into which come and through which flow the high frequency oscillations. Now, as said high frequency oscillations flow through the existing and continuous field of electro-magnetic energy, said high frequency oscillations are, in effect, magnified, or there is produced an algebraic total of the effects of both the electro-mag-

netic energy produced by the constant current, and of the high frequency oscillations, and said total effect is greater upon the detecting instruments than the effect 5 of the high frequency oscillations alone would have been. Therefore, my invention results in magnifying the effects of the high frequency oscillations beyond what their effects would have been, as received from 10 the distant sending station, if they had not been, so to say, strengthened by the addition of the constant current electricity to the aerial.

But, as the constant current which is 15 added to the aerial is of such strength that it would improperly affect the detecting instrument, if said constant current were permitted to reach the detecting instrument, said constant current must be prevented 20 from reaching the detecting instrument, although said constant current must continue to flow along some part of the aerial so as to always produce the constant independent field of electro-magnetic force. Now I 25 prevent said constant current from reaching the detecting instruments and improperly affecting them when the high frequency oscillations are not coming along on the aerial, by interposing resistances which said constant 30 current cannot pass through between the generator of said constant current and the detectors. Such a resistance to the passage of constant current is a condenser, as is well known, and I also may use a high 35 non-inductive resistance between the generator of the constant current and said detecting instruments.

Thus this invention provides, on the one hand, for continuously supplying a current 40 of electricity to some part of the aerial along which travel the high frequency electric oscillations on their way to the detectors; and on the other hand I interpose resistances between the generator of said constant 45 currents and the detectors, which prevent the passage of said constant currents to the detectors when the high frequency oscillations are not traveling on said aerials. When said high frequency oscillations are 50 traveling on the aerial, the total effect of the constant current and the high frequency oscillations is some algebraic total, or some function, of the strength of both the constant current electricity and the high frequency 55 oscillations, and said high frequency oscillations, being thus strengthened, and, as is well understood, not being prevented from reaching the detectors by the condensers or the non-inductive resistances, 60 flow freely across the condensers, or through said non-inductive resistances, with their strength much increased over what their strength would have been had the constant current not have been caused to flow along 65 the aerial.

The foregoing explanation will make it clear that although the detector is not in that part of the aerial which is affected by the independent constant current, yet it is operated by the high frequency oscillations, for said high frequency oscillations travel along the whole extent of the aerial, not being checked by the condenser or other high non-inductive resistance; and therefore said high frequency oscillations reach 70 and affect the detector. Said explanation will also make it plain that the resistances, that is, either the condenser or the high inductive resistances, do prevent the independent constant current from reaching the 75 detector; or, as I explain it, said condenser or said high inductive resistances do "insulate" the detector from the independent constant current, so that said independent constant current does not affect the detector 80 when the high frequency oscillations are not traveling on the aerial. But, in that case, said independent constant current simply flows around and around on its parts of the aerial which is connected with the independent generator; and through said connecting wires and generator, and continues to flow around and around in its own independent circuit while said high frequency oscillations are not being received on the aerial. 85 When said high frequency oscillations are being received on the aerial, they flow through the field of force that has been developed around the aerial by said independent constant current, and are strengthened 90 thereby. Said high frequency oscillations of course maintain the same frequency of vibration or alternation that they had before entering said field. The effect of said field which is produced by said constant 95 current is to algebraically add to the strength of the high frequency oscillations, and give to said high frequency oscillation a power to influence the detector, that is greater than such high frequency oscillations, as received from the distant sending station, would have had had the independent constant current not been applied to the aerial generated the independent field of electro magnetic force around said aerial. 100

I also prefer to employ, in connection with said field, my intensifying tubes, or conductive sheaths, which inclose the aerials, and are in the closest practicable proximity thereto, but are insulated from said aerial; 105 and I may connect said tubes, or not, with electric generators to produce independent fields of energy around and within said tubes. But said tubes may also be employed in connection with the independent fields of 110 energy about the aerials, without said tubes being connected with generators or being independently charged.

Since this invention relates to the process, which is not restricted to any particular ar- 115

rangement or construction of apparatus to operate it, I illustrate in the drawings which accompany this specification only certain apparatus, which are sufficient to clearly set forth the invention, and how the same may be constructed and operated.

Referring to said drawings, which illustrate various constructions and arrangements of apparatus in a diagrammatical manner, Figure 1 is an elevation of a close-coupled system for operating the invention. Fig. 2 is an elevation of an inductively coupled system. Fig. 3 is a broken elevation of an inductively coupled system provided with my intensifying tube. In this figure the intensifying tube is shown connected with its own independent electric generator. Fig. 4 is a cross-section, on a larger scale, of an intensifying tube, aerial and insulating disk. Fig. 5 illustrates another arrangement of the invention with intensifying tubes, and wherein the intensifying tubes are arranged on the parts of the wires which are as near practicable to the detector. In this figure the intensifying tubes are shown as not connected with electric generators. Fig. 6 illustrates an arrangement of an aerial with the intensifying sheath arranged as a coil of insulated wire, coiled around the aerial. This construction I term a "compound aerial". Fig. 7 is a broken elevation, on large scale of an intensifying tube and aerial, as constructed of relatively short lengths or pieces. Fig. 8 is a cross-section on large scale of the intensifying tube constructed of half tubes flanged together.

In the several figures the detector is represented as a coherer, but may be of any type, as a crystal detector, electrolytic detector, rectifying detector or any other type; and is also to be understood, that while the invention is particularly adapted to use in wireless telegraphy, it is not restricted thereto; but is also applicable to various other purposes for which the employment of high frequency electric oscillations is advantageous, as for the control of explosions of machines and torpedoes and other purposes, as well in naval and military operations as in civil enterprises.

Now referring particularly to the aforesaid Fig. 1 of the drawings, A being the antennæ of a receiving station, B the aerial, and A¹ a condenser or other high resistance which may or may not be used to prevent the independent current from flowing to and possibly leaking from the tips of the said antennæ, the said independent field is generated about a part of the path traversed by the high frequency oscillations as they travel from the said antennæ to the detector, D, by connecting such part of said aerial B, as it is desired to so connect, with independent generator of electric current G, so that

said generator will constantly maintain a field of electro-magnetic energy about the part of said aerial B, which is connected with said generator G,—that is, the part of said aerial B between the circuit wires g and g¹, which connect said generator G with the desired points on said aerial B. Thus the operation of said generator G will continually maintain a flow of current electricity along said part of said aerial B, and thereby generate and maintain a field of energy about said part of said aerial wholly independent of the Hertzian waves received by said antennæ A and of the high frequency electric oscillations set up on said aerial B by said waves. But, as said aerial B provides the path along which said oscillations vibrate on their way to said detector D, said oscillations must pass through said field, and are thereby re-invigorated, or "relayed" by said field, and their effect on the said detector D is increased over what their effect would have been had not said oscillations been so "relayed" by said independent field.

Said generator G is preferably a constant current generator. The current generated by said generator G is of such strength that it would normally improperly operate the detector D, if said current could reach said detector; and therefore it is necessary to electrically separate or insulate said generator G and the independent current thereby generated from said detector; and this is effected by placing a condenser C, or other suitable non-inductive resistance, between the said detector D and the junction of the circuit wire g¹ (which, as well as wire g, is preferably insulated wire) with said aerial B. That is to say, the circuit wires g—g¹ of the generator G, so to say, short circuits said condenser or resistance and detector, and the said independent current will flow around in the closed circuit formed by the aerial B, the said wires g—g¹, the choke coils, generator and resistance, and will not reach and improperly affect said detector D; and it is only when the high frequency electric oscillations traverse said independent field and are thereby re-invigorated or relayed, that said detector D is operated.

I prefer to place an adjustable resistance R in the generator circuit, and to employ choke coils K K to prevent high frequency oscillations from passing into the said generator circuit.

If it is desired to employ the same antennæ A and aerial B for sending and receiving, a switch, diagrammatically represented by S, may be arranged so that the installation may be used either for sending or for receiving; and in the several figures of the drawings said switch is indicated as in the position for receiving, ² being a contact in the wire p, which leads from the oscillator—not shown.

The local circuit, indicated in various figures by the wires $t-t'$, will be equipped with the usual instruments.

The operation of the aforesaid apparatus 5 will be apparent from the foregoing explanations and descriptions with but little further explanation. The operation of the independent generator G continually maintains a relatively strong electric current, 10 and a correspondingly strong independent field, around the desired part of the said aerial B. Through this independent field pass the high frequency oscillations to the detector D, and are by such passage, re- 15 invigorated and "relayed" so that they affect the detector more energetically and usefully than they would have done had not such independent field been developed and maintained; while the use of said field in- 20 creases the control which the operator at the receiving station has over his apparatus and system.

In said Fig. 1 the detector D is shown connected in series by the condenser C, with 25 the aerial B and grounded by the wire f. In Fig. 2, which illustrates an inductively connected system, said detector is in closed-circuit connection, by the wires $e^1 f^1$, with the secondary of the transformer T T¹, 30 which is preferably a variable transformer, and a high resistance X, non-inductive, is employed instead of a condenser to insulate said detector D from the independent current, although a condenser could be em- 35 ployed in place of said resistance X. Of course, instead of resistance X, a condenser might be used, and in place of condenser C in Fig. 1 a high resistance might be em- 40 ployed.

40 In Fig. 2 a condenser C¹ is shown in the generator circuit and in series with said generator G. Said condenser C¹ becomes charged up to the point at which its counter electro-motive force equals that of said generator G, when no further charge flows into said condenser.

The operation of the apparatus of Fig. 2 will be clear without further explanation, the oscillations flowing freely across con- 50 denser C¹.

Fig. 3 diagrammatically illustrates a system wherein my intensifying tube H is used along with the said independent field; and in this figure both the said aerial B and said tube H are connected with their independ- 55 ent generators G and G¹ respectively, so that independent fields are generated both around said aerial B, and in and around said tube H. I have found by actual ex- 60 perience, that when a wire on which high frequency oscillations are vibrated, is surrounded by a metal sheath which is very near to the wire, but is insulated therefrom, then, when said high frequency oscillations 65 are vibrating on said wire, they set up an

active excitation between said wire and said sheath, so that said sheath becomes intensely excited, and will spark vigorously if a bit of metal be held near it. This invention *per se* has been patented by me in a 70 patent dated August 7th, 1917, No. 1,235,650, and said patent has shown the opinion of the Patent Office that the facts are as stated in the specification of said patent. Just why said sheaths become excited under said 75 circumstances, does not appear to be certainly clear, but the fact is undoubted, and as has been before stated, it is set forth in patent in said United States Patent, No. 1,235,650. In place of having separate gen- 80 erators, both said aerial and said tube might be connected with the same generator; and I prefer that the direction of the independent current shall be the same on the aerial and the intensifying tube; choke 85 coils and adjustable resistances being applied to the circuit connections of both said aerial and said tube, as indicated in Fig. 3. Of course the independent electric current on said aerial B must be electrically 90 separated or insulated from said detector D, as by condenser C or other suitable means as a high non-inductive resistance. Since said intensifier tube H is carefully 95 insulated from said aerial B by the insulated disks i (Fig. 4) or other insulation, it will not be necessary to further insulate said tube H from the detector.

Said tubes H are of electrically conductive material, preferably copper, and are 100 preferably of the smallest diameter to inclose said aerials B and yet be insulated therefrom, since the efficiency of said tubes H depends upon the close proximity of the walls of the tubes to the aerial, while nevertheless said tubes are insulated from said aerials. Such insulation may be effected in various ways, as by insulating disks i placed at proper distances apart in said tubes H, and through the centers of which said aerial B passes, and said disks i may be perforated or notched to permit circulation of air, if desired, to diminish tendency to over-heat. I have found that said insulating disks may be conveniently constructed by winding 115 adhesive insulating tape around the aerial, at proper intervals to form plugs loosely fitting said tubes H. Cap j of non-conductive material may be secured on said aerial B above said tube H to keep out moisture, 120 and a non-conductive shoulder or stop m, (See Fig. 3) may be secured on the said aerial at the other end of said tube H to prevent longitudinal displacement of said tube.

125 It will be understood that, with the construction of Fig. 3, an independent field is maintained both around said aerial B and within and around said tube H, by traversing which fields said high frequency oscil- 130

lations will be re-invigorated, and their effect upon the detector increased.

Even when the said intensifying tubes are not charged with an independent current, their effect to set up intense reactions between the aerial and the tubes is great, and they are therefore useful of themselves in connection with said fields on the aerials. Such an installation is indicated in Fig. 5 5 wherein said tubes H, H are placed on the wires e¹ f¹ of the closed detector circuit and so as to be in the nearest practicable position to the director D, this being an advantageous position for said tubes.

10 In Fig. 3 said tube H is indicated as made in long pieces, but it may be very conveniently constructed of short lengths, abutting at the ends, with good connecting fit, Fig. 7, and electrically connecting pieces or sleeves or may be used at the joints. The aerial B may also be constructed of relatively short lengths, united by electrically conductive couplings insulated by plugs W from contact with the ends of the lengths 15 of the tube.

The lengths of the said tubes may also be conveniently constructed as half-tubes H² H³ (Fig. 8) with longitudinal flanges l² by which they are fastened together around the aerial B, and the insulating disks i³, may also be constructed of half disks i³, secured at proper intervals in said half tubes H².

In Fig. 6 the intensifying sheath Z is indicated as constructed of a coil of insulated 35 wire coiled around the aerial B. In this figure said coil Z is indicated as connected with the independent electric generator G², preferably of constant current, and the direction of the flow of the current is the 40 same generally as in the aerial B; and the same generator may be connected both with said aerial and said coil Z. When said coil Z is charged, choke coils K² K³ and variable resistance R² will preferably be provided 45 in the circuit of said coil Z.

Now, having described my improvements I claim as my invention—

The process of increasing the effect of 50 high frequency electric oscillations on detectors, which consists in generating and continuously maintaining independently of said oscillations an electromagnetic field about a part of the aerial on which said oscillations vibrate, whereby said oscillations are invigorated and their effect on said detectors increased, and insulating said field from said detectors so that normally said detectors are not improperly affected by said field.

Signed at Atlantic City, in the county of Atlantic, State of New Jersey, this 3rd day of August, 1917.

DAVID W. BROWN.

In the presence of—
CHARLES H. PARSONS.
